UNITED STATES PATENT OFFICE.

WILLIAM C. LADD, OF MENDOTA, ILLINOIS.

BALL-CLAMP.

SPECIFICATION forming part of Letters Patent No. 759,533, dated May 10, 1904.

Application filed August 6, 1903. Serial No. 168,492. (No model.)

To all whom it may concern:

Be it known that I, WILLIAM C. LADD, a citizen of the United States, residing at Mendota, in the county of Lasalle and State of Illinois, 5 have invented new and useful Improvements in Ball-Clamps, of which the following is a specification.

My invention relates to work-clamps; and its primary object is to provide a new and useful 10 device of this character by means of which a base-ball may be held while its cover is being secured in applied position.

A further object of the invention is to provide a simple and cheap yet durable device of 15 this character which will be composed of few parts and those so arranged as to avoid liability of becoming inoperative.

A still further object of the invention is to provide a work-holder which may be either 20 held within the hand, readily and quickly secured between the jaws of a stitching-horse, or secured in a slot arranged in a work-bench while the cover of a ball is being secured in applied position.

25 With the above and other objects in view the invention consists of the construction, combination, and arrangement of parts hereinafter fully described, claimed, and illustrated in the accompanying drawings, which disclose the 30 preferred form of my invention, and in which—

Figure 1 is a perspective view of a clamp constructed in accordance with my invention, the same illustrating the manner in which a 35 ball is adapted to be held while its cover is being applied. Fig. 2 is a central longitudinal sectional view thereof, illustrating the clamp secured between the jaws of a stitching-horse. Fig. 3 is a view similar to Fig. 2, illustrating 40 the clamp secured in a slot arranged in a work-bench.

Referring to the drawings by reference-numerals, 1 and 2 designate members hingedly connected at their lower ends and having their 45 upper free ends provided with jaws 3, between which a ball is adapted to be clamped to retain it in a rigid position while its cover is being applied. The members are formed from any suitable material, and their longitudinal

edges are reversely bent to provide flanges 4, 50 having their lower portions apertured for the reception of a pintle 5, which hingedly connects the members. The jaws 3, which are formed by depressing the upper or free ends of the members, are cup-shaped and of a depth 55 sufficient to permit a ball to be grasped between the jaws to prevent it from turning and also to expose the greater portions of the meeting edges of its cover to give free access for the purpose of stitching the cover. Tangs 6 60 are struck up from the members to project laterally from the outer sides thereof, the purpose of which will be hereinafter fully set forth.

The operation of the clamp may be explained in the following manner: A ball is first provided with its cover and then inserted between the jaws 3, which are caused to approach each other to hold the ball against movement while its cover is being stitched. 70 The clamp may be held within the hand or between the jaws of a stitching-horse during the operation of stitching the cover. When the clamp is held between the jaws of a stitching-horse, the tangs 6 are adapted to engage the 75 under side of said jaws to prevent the clamp from having any upward movement, and the inclination of the members, caused by the grasping of a ball between the jaws, prevents the holder from having a downward movement, thereby permitting the clamp to be rigidly secured between the jaws of a stitching-horse. When the jaws are constructed from wood, the tangs 6 may be caused to penetrate 80 their faces, and thereby prevent any movement of the clamp. The application of the holder to a slot in a work-bench, as disclosed in Fig. 3 of the drawings, may be accomplished in a manner that is obvious. It may be further stated as the members of the clamp 85 are provided with a plurality of the tangs 6, arranged in horizontal alinement and adapted to engage the under surfaces of the jaws of a stitching-horse or a slot, that the clamp is prevented from having an oscillating movement 90 in its applied position.

It is apparent that the clamp may be used for the purpose of clamping any article which

is spherical, or approximately so, in contour as readily as it may be used to hold a baseball.

Having thus described the invention, what is claimed as new is—

1. In a device of the character described, the combination with the jaws of a stitching-horse, of a clamp comprising members hingedly connected together at their lower ends and having their upper ends provided with jaws, and tangs carried by said members and arranged in horizontal alinement to engage the under surfaces of the jaws.

2. A device of the character described, comprising two members having their longitudinal edges provided with flanges, a pintle adapted to engage the flanges to pivotally connect the members, cup-shaped jaws formed on the free ends of said members, and tangs struck up from the members.

3. A device of the character described, comprising members, each having one of its ends provided with a cup-shaped jaw, a pintle adapted to engage the opposite ends of the members to hingedly connect them together, and tangs struck up from the members.

4. A device of the character described, comprising members, each having one of its ends provided with a cup-shaped jaw, a pintle adapted to engage the opposite ends of the members to hingedly connect them together, and tangs struck up from the members, the tangs on each member being disposed in horizontal alinement.

In testimony whereof I affix my signature in presence of two witnesses.

WILLIAM C. LADD.
